TEMPERATURE CONTROL FOR REFRIGERATOR CARS

Filed Nov. 8, 1941

UNITED STATES PATENT OFFICE

2,390,993

TEMPERATURE CONTROL FOR REFRIGERATOR CARS

Clarence A. de Giers, Forest Hills, and Arthur Wickesser, St. Albans, N. Y., assignors to The Liquidometer Corporation, Long Island City, N. Y., a corporation of Delaware

Application November 8, 1941, Serial No. 418,366

3 Claims. (Cl. 236—80)

This invention pertains to apparatus for the control of temperature in a space. The invention has a great variety of uses, but since it was developed for control of temperature in refrigerator cars in transit the invention is, for convenience, described in that connection, but it is not limited to that particular use.

While cars are transporting perishable goods, it is necessary at times to supply heat, and at other times to remove heat. The removal of heat is usually brought about by ice carried in the car. An object of the present invention is to disclose apparatus for supplying heat whenever needed, and for automatically controlling that supply in such manner as to maintain the car temperature within close limits.

Another object is to disclose an apparatus simple in design and construction and suitable for installation in a compartment under the floor of the car and readily accessible from outside the car when desired.

Another object is to disclose an apparatus in which each of its operations is positive in action even under the severe service to which a refrigerator car is subjected.

This invention is an improvement on the invention disclosed in copending application Serial No. 418,365 filed November 8, 1941, by the present inventors and entitled "Remote regulation of atmospheric condition." Said application has matured into Patent No. 2,371,428, dated March 13, 1945.

Further and other objects and advantages will be apparent from the specification and claims, and from the accompanying drawing which illustrates what is now considered to be a preferred embodiment of the invention.

The drawing shows the invention largely in diagrammatic form, unessential details being omitted.

Bulb 10 is located in the car and is connected by open-end tube 12 to bellows 14, the bulb and bellows being full of liquid 16. Another tube 18 with a closed end at the bulb connects in like manner to bellows 20, similar to bellows 14 but differently supported.

Bellows 14 and 20 are enclosed in an instrument case 21 having a back plate 22.

Bellows 14 is attached at its outer end to plate 22 by bracket 24. Bellows 20 is attached to plate 22 by bracket 26 intermediate the ends of the bellows.

The axes of the bellows are parallel but offset, their inner ends being pivotally connected by studs 28 and 30 to opposite ends of a floating link 32. An arm 34, fulcrumed at 36 on plate 22 is pivotally connected by pin 38 to the center of link 32. Mounted on the upper end of arm 34 is a cam roller 40.

As disclosed in deGiers Patent No. 1,943,267,

issued January 9, 1934, this arrangement of offset similar bellows, liquid-filled and connected by a floating link, is effective to prevent movement of arm 34 due to changes of temperature of the bellows or tubes connecting them to bulb 20. However, when a change of temperature occurs in the car and therefore in bulb 10, liquid 16 therein will expand or contract and some of the liquid will be forced into or out of tube 12, causing bellows 14 to expand or contract axially, thereby swinging lever 34 about its fulcrum 36 through the instrumentality of link 32, the lower end of which is stationary at an adjusted position. Briefly, the position of lever 34 is dependent on the position of pin 38 (in link 32), and the position of pin 38 is dependent upon the action of bellows 14, at one end of the link, in combination with the manual adjustment at the other end thereof.

In the device of the above mentioned deGiers patent, any change of bulb temperature is simply indicated by a pointer, but in the present invention means are provided for adjusting the temperature to a predetermined value, the desired temperature being indicated by a manually adjustable lever 42 in cooperation with a graduated dial in the form of a disk 44 on the outside of case 21.

Lever 42 is attached by pin 46 to the outer head of a spindle 48 in axial alignment with bellows 20 and rotatable by lever 42. The inner end of the spindle is threaded at 50 into the head 52 of bellows 20. When the spindle is rotated, collars 54 and 56 prevent lengthwise movement of the spindle, thereby causing threads 50 to move bellows head 52 axially, thus either lengthening or shortening bellows 20. Since bellows 20 is filled with incompressible liquid, and is fixedly mounted to the case by bracket 26, the movement of head 52, acting through stud 30, adjusts the position of the lower end of link 32, and, through pin 38, affects the movement of lever 34 about its fulcrum 36. Spindle 48 is enclosed in a bellows 49 sealed at one end to head 52 and at its other end to the wall of case 21.

Lever 42 is held in its adjusted position by a boss 58 on the lever engaging an appropriate socket 60 in disk 44. A spring 62 holds boss 58 in the selected socket until manual depression of the other end of the lever frees the boss to permit movement to another selected position.

When heat is needed in the car it is supplied by a gas heater 64 which warms a heat-exchanger 66 from which fluid circulates through suitable radiators in the car. The fluid is usually a solution of ethylene glycol and water. The fuel gas is usually propane, furnished in liquefied form in drums which are held in racks underneath the car. The drums are equipped with a regulator valve through which gas at suitable pressure

reaches heater 64 through pipe 68, as will appear, being introduced into the apparatus through pipe 70 which leads to chamber 72 underneath diaphragm 74 in valve housing 76.

A branch pipe 78 leads from pipe 70 to instrument casing 21 and keeps the interior of the casing filled with gas under pressure.

Casing 21 contains a valve 80 from which a pipe 82 leads to chamber 84 above diaphragm 74.

Adjacent heater 64 is a pilot burner 86, under control of pilot valve 88. Burner 86 serves the double purpose of, first: igniting gas in heater 64 when gas is supplied to the heater, and second: keeping hot the thermostatic element 90. Gas reaches burner 86 from pipe 70, through pipe 92, 10 annular passage 94 in valve 88, chamber 86 and pipe 88. A valve disk 100 pressed upwardly by a spring 102, closes the lower end of passage 94 except when depressed, as in the drawing, by plunger 104 which has a head 106 upon which rests the horizontal arm 108 of a bell crank pivoted at 110 and having a vertical arm 112 in contact with element 90. A bellows 114 seals plunger 104 from the atmosphere. Pipe 116 connects chamber 84 with annular passage 94 in valve 88. 25

When temperature of bulb 10 in the car is at the desired temperature, as indicated on disk 44, lever 34 and its cam roller 40 are in the positions shown in the full lines of the drawing, and the orifice of valve 80 is closed by disk 118. The disk is mounted on a downwardly extending arm 120 of a cam member 122 pivoted at 124. The cam has an arcuate arm 126 extending to the left and an arcuate arm 128 extending to the right.

If the temperature of bulb 10 should rise above the temperature desired, bellows 14 will have elongated beyond its normal length, link 32, its upper end actuated by stud 28, will, through pin 38, have moved the lower end of lever 34 to the left and the upper end thereof to the right, causing roller 40 to push against, and possibly pass over, shoulder 130, thereby rotating cam assembly 122 about its pivot 124 and opening valve 80 by moving arm 120 and disk 118 to their dotted line positions, in which positions they are positively maintained by roller 40 rolling along the top of arcuate arm 128, as indicated by the dotted lines of the drawing. Spring 132 prevents lost motion and back-lash in the cam assembly. While valve 80 is open gas entering instrument case 21 through pipe 78 flows through pipe 82 into space 84 above diaphragm 74, and thence through pipe 116, through valve 88 and pipe 88 to be burned in pilot burner 86. The pressure of this gas on diaphragm 74, plus the pressure exerted by spring 134, serves to depress the diaphragm until disk 136 attached to the underside of the diaphragm rests on valve seat 138, thus preventing flow of gas from pipe 70, through chamber 72 into supply pipe 68, and extinguishing the flame in heater 64, thus permitting the refrigerator space to cool.

When the car temperature drops below normal, bellows 14 shortens, lever 34 swings to the left, and roller 40 rolls along the arcuate top of arm 126, the center of which is at 36, thus positively holding disk 118 against the inlet opening of valve 80. When this occurs, the gas in pipe 82 and space 84 will exhaust through pipe 116 and valve 88 to be burned at pilot 86. Diaphragm 74, thus relieved of gas pressure above it, is raised by the gas pressure in chamber 72 against spring

134, thus lifting disk 136 from its seat 138 and allowing gas to pass through pipe 88 to heater 64 where it is ignited by burner 86, whereupon heat is again supplied to the car through heat exchanger 66. The relation of the effective internal diameters of the pipes 88, 92, and 116 is such as to prevent backflow from the pipe 92 into the pipe 116 during the normal operation of the system.

The apparatus is put into operation by manually depressing horizontal arm 108 to open valve 100 and permit gas to flow to pilot 86. After the pilot is burning and element 90 is heated thereby, valve 100 remains open and the device operates automatically as described so long as gas is supplied.

The device illustrated and described will give sufficiently accurate results for ordinary use, but if the requirements as to accuracy are unusually stringent, the improvements of deGiers Patent No. 2,050,965 may be added to the device here-with illustrated.

It is to be understood that the invention is not limited to the refrigerator car embodiment herein illustrated and described, but may be used in other ways without departure from its spirit as defined by the following claims.

What is claimed is:

1. Apparatus for controlling temperature in a refrigerator car, comprising in combination, a pair of bellows, a floating link differentially interconnecting said bellows, means causing change of length of one of said bellows in accordance with change of temperature in said car, manually controllable means for changing the effective length of the other of said bellows for the purpose of adjusting the temperature to be maintained in the car, a heater for supplying heat to said car, and means under control of said link for controlling said heater.

2. In apparatus useful for controlling temperature in a refrigerator car, in combination, a pair of bellows, a floating link differentially interconnecting said bellows, means causing change of length of one said bellows in accordance with change of temperature in the car, manually controllable means for changing the relative effective length of said bellows for adjusting the temperature to be maintained in the car, heating means for supplying heat to the car, and means under control of said link for controlling said heating means.

3. In combination, a plurality of bellows, control means operated by said bellows and including a floating link differentially interconnecting two of said bellows, means including a thermally responsive device connected to one of said link-connected bellows for changing the effective length of said last mentioned bellows in accordance with changes in temperature at the locus of said thermally responsive device, means responsive to changes in temperature between said locus and said bellows for changing the effective length of the other of said link-connected bellows, heating means for supplying heat at the said locus, means under the control of said link for controlling said heating means, and manually settable means for changing the effective lengths of at least one of said bellows for adjusting the temperature to be maintained at the said locus.
